UNITED STATES PATENT OFFICE.

CHARLES I. MATSON, OF CHICAGO, ILLINOIS.

AERIAL MACHINE.

1,036,667.

Specification of Letters Patent. Patented Aug. 27, 1912.

Application filed June 8, 1909. Serial No. 499,833.

To all whom it may concern:

Be it known that I, CHARLES I. MATSON, a citizen of the United States, residing at Chicago, in the county of Cook and State 5 of Illinois, have invented certain new and useful Improvements in Aerial Machines, of which the following is a specification.

My invention relates to appliances for navigating the air and has especial reference 10 to heavier than air machines and particularly to apparatus in which the supporting elements are in the form of planes.

Aeroplanes as ordinarily constructed are rigid over their entire area, and when in operation have a gliding movement the line of direction deviating by small angles from the plane of the structure. Appliances employing this type of passive mechanism are largely dependent for buoyant power upon 20 the force with which the air particles are projected against the surface of the plane, reliance thus being placed either upon the natural atmospheric currents, or the inertia 25 of the colliding particles while the plane is in flight or both factors combined to produce the required lifting or supporting effect. As previously stated the angle which the plane makes with the bodily movement is necessarily a slight one, and the lines of 30 force are usually directed at such an inclination to the plane surface that a large amount of the available power is lost.

The chief objects of the improvements which form the subject matter of this application are:—to produce a machine of the type specified employing plane supporting surfaces, so arranged and constructed that the planes may be moved in a direction at right angles to their surfaces thus causing 40 the lines of impact of the air particles to bear such a relation to the surfaces against which they collide as to receive practically their full force, an advantage not to be obtained by the ordinary construction; to furnish a series of planes arranged to be operatively moved in alternation so that the supporting forces may be applied in a practically continuous manner, and to adapt the planes to be inclined bodily to the main portion 45 of the structure in order to give the apparatus a trend in a forward or backward direction, in addition to the vertical movement.

Other objects are, to provide steering 50 means by relative movements of the planes; to arrange the planes and operative mechanism in such a manner as to produce a

proper equilibrium of the apparatus, to furnish a sufficiently rigid structure combining strength and lightness, and to so design the 60 mechanical parts that the required lifting power may be furnished by an apparatus of comparatively moderate dimensions and simple in its mechanical movements, thus producing a machine that will be economical 65 to build and that will present a comparatively light weight.

I accomplish the objects above set forth and others of importance, by means of the 70 appliance illustrated in the accompanying drawings, the main features comprising a platform carrying the motor and coöperating mechanism, a series of frames supported upon standards above the platform, planes arranged to reciprocate with said frames, 75 said planes being formed of hinged valves or vanes; operative means for reciprocating the planes, means for deviating the angle of the planes relatively to the said platform, and steering means.

The important details of construction are disclosed in the following views:—Figure 1 is a rear elevation of the entire apparatus; Fig. 2 is an end elevation; Fig. 3 is a top plan view of the middle portion of the apparatus, a part of the superstructure being broken away to disclose the mechanism beneath; Figs. 4 and 5 are fragmentary views enlarged showing the manner of supporting the vanes; Fig. 6 is a fragmentary view 90 showing a corner of one of the planes, seen from the underside, and Fig. 7 is a transverse section through a modified form of vane.

Referring to the details of the drawing 95 the numeral 10 indicates a supporting platform, rectangular in outline, and having its end portions 11 narrower than the central portion to reduce weight. This platform is rendered rigid by a longitudinal tie rod 12 100 running beneath the platform and connected thereto at each end, posts 13 being interposed between the rod and under side of the platform, thus forming an effective truss which in connection with the platform 105 forms a supporting frame. Extending transversely beneath the frame are arranged a pair of light resilient supports, in the form of runners 14 upon which the apparatus rests when not in operation, the supports 110 also acting as buffers when alighting. The members of the truss supporting the platform are preferably made of suitable tubing, and the runners or buffers constructed of

some variety of wood, such as hickory, which will have the required toughness to allow of being bent to the required shape.

Arranged in the median line is a main shaft 15 journaled in boxes 16 mounted on brackets 17, located in pairs at spaced intervals. This shaft is operated by a suitable motor 18 carried on the platform 10 and connected by a sprocket chain 19 with a sprocket wheel 20 loosely mounted on said main shaft, the said wheel being thrown into and out of gear with the shaft by means of an ordinary clutch 21 operated by a lever 22. Between each pair of brackets the main shaft is provided with a crank 23, and upon the shaft at either side of each crank is mounted a loose sleeve 24, retained in position by a collar 25. Projecting upwardly from these sleeves are standards or guide rods 26 composed of tubing to render them sufficiently light and connected at their tops by a tie piece 27. Each pair of these guide rods carries a light rectangular reciprocating frame, preferably made of suitable steel tubing, secured at the joints by brazing. There are four of these frames, similarly formed and constructed as follows:—The basic members of each frame consist of two sleeves 28 mounted to slide upon the said guides 26 and are connected at each end by tie pieces 28^a. Extending horizontally from the top and bottom of these sleeves are tubular members 29, lying in the same plane, which coincides with the axis of the main shaft, and connected at their outer ends by vertical members 30, auxiliary posts 31 rising from the upper horizontal member 29, the members 30 and posts 31, supporting a horizontal framework, also rectangular in outline and extending equally upon both sides of the vertical frame, as shown in Figs. 2 and 3. These horizontal frames comprise four parallel members 32, connected at their extremities by end bars 33, cross pieces binding the parallel members 32 together between the ends. Each member 32 is reinforced by piano wires 36 which are attached at the extremities and suitable intermediate points of said members and carried over posts or struts 35 erected at the middle points of the members 32. Auxiliary piano wires 36 are connected at one end to the frame members 32 and at the other are brought down and made fast to the lower part of the vertical frame, as shown in Fig. 2. Each vertical frame is reciprocated upon the guides 26 by means of a hollow connecting rod 37, attached at the lower end by a box 38 to the corresponding crank 23, and journaled at the upper end on the lower cross pieces 28^a, a suitable boxing 38^a being provided at this point.

Each horizontal frame is furnished upon the under side with a series of hinged vanes 39, having their margins over-

lapping when the said vanes are in their horizontal or operative positions, as shown at 40 in Figs. 4 and 6. The manner of hinging and supporting the said vanes 39 is shown in detail in Figs. 4, 5, and 6. I prefer to form these vanes in comparatively long and narrow sheets or strips and use for this purpose any suitable strong, light fabric. I have found certain grades of paper to be sufficiently firm and tough for these vanes, and when treated with some suitable waterproof varnish will not be affected by dampness. I provide a hinge for each vane by stretching parallel cords 41 across the frame at proper intervals and attaching one margin of the vane thereto by a suitable adhesive. The position of these cords relatively to the attached sheet or vane is shown in Figs. 4 and 5. It is necessary to control the movement of the free margins of these flaps or vanes in both directions, either up or down, and to limit the upward movement I stretch stop wires or cords 42 across the frame at suitable intervals and so positioned that the flaps will lie in contact therewith when carried upward by the impact of the air, and when in this position the overlapping vanes will form a continuous sheet or plane extending over the entire area of the horizontal framework the flaps lying sufficiently close to prevent the air from passing through. To limit the downward movement of the individual vanes I furnish a damping wire or cord 43, stretched parallel with the stop and hinge cords, and arranged in proximity to the hinge margin, as shown in the drawing.

Extending rearwardly from the main bracket 17 are auxiliary brackets 44, which carry a compound or telescopic rock-shaft comprising an outer and an inner tubular shaft arranged to rock independently or together in a manner to be described. The outer shaft comprises two similar sections 45, 46, rigidly connected at the middle point of the machine by an offset 47. These sections extend between the two middle pairs of main brackets 17 and are rocked in their bearings by means of a worm 48 mounted in an arm 49, extending from the adjacent bracket 44. This worm meshes with a gear 50 mounted on the shaft section 45, and is operated by a hand wheel 51. Within the outer rock shaft is mounted a hollow inner shaft 52 also consisting of two sections. Both inner sections project entirely through their respective outer sections, and carry upon their inner ends beveled pinions 53, which mesh with a common gear wheel 54 journaled on the said offset or shaft connection 47. The outer ends of the inner sections extend to the outer brackets 17 so that the inner rock shaft in its entirety is equal in length to the main crank shaft 15. Upon

one of the inner sections adjacent to the pinion 53 is a rock-lever 55, keyed fast to the section, and furnished with a spring held pawl operated by a latch 56, said pawl being arranged to engage a series of spaced notches 57, formed in a sector 58 secured to the corresponding section 46 of the outer shaft.

The standards 26 are operatively connected to the rock shaft in the following manner: The shaft sections are furnished with vertical rock arms 59, each arranged to correspond with a pair of the said standards, and this arm is connected by a link 60 to a fork 61 the branches of which are attached to the corresponding standards or guides 26 by collars 62.

It will be evident that when the pawl of the lever 55 is in engagement with one of the notches in the sector 58, the inner and outer rock shafts will be locked together through the intermeshing of the gears 53 and 54 and will turn as one shaft when the worm 48 is operated, and whenever the shafts are so rocked the standards 26, carrying the said reciprocating frames, will be correspondingly rocked upon the main shaft, thus inclining the planes carried thereby forward or back to the required angle, this inclination of the planes causing an upward or downward deviation of the course of the apparatus when in motion. In order to turn the machine either to the right or left the lever 55 is released from its engagement with the outer shaft, and moved forward or back to the required angle, where it is retained by the hand of the operator, or locked in its new position by allowing its pawl to engage a notch in the sector 58. The manner of coupling the inner rock-shaft sections together by means of the gears 53 and 54 will cause the said sections to be rocked in opposite directions when moved independently of the outer shaft by the described movement of the said lever 55, so that the reciprocating planes on the extreme right and left will be inclined in opposite directions, and the resistance which they offer to the air when in that position being contrary to each other, there will be a tendency to turn the entire structure horizontally upon its center, and this steering or guiding action will take place regardless of the relative positions of the middle planes.

A modified construction for the vanes is shown in Fig. 7. This form is advantageous especially when a woven fabric is made use of for the body of the flap, which is made by doubling the sheet 63 around a single wire 64, about which it will turn as on a hinge, stiffening strips 65 of some suitable material being placed at intervals between the layers.

The functions of the various parts having

been mentioned in connection with the detailed description of the construction, a general explanation of the operation of the mechanism as a whole will be sufficient to give a clear understanding of the manner in which the appliance will be elevated, moved in its course forward or backward at an upward or downward angle, guided either to the right or left as occasion demands, or turned upon its vertical axis.

When at rest the apparatus will be supported upon the runners 14, which are formed with upturned ends, as shown, in order that they may offer no obstruction in case there should be a forward or backward movement when starting or alighting. To elevate the apparatus the main crank shaft 15 is set in motion and through the action of the connecting rods 37 the reciprocating frames will be alternately raised and lowered, the cranks 23 being so arranged that the two middle frames will move in unison, but in a reverse direction to the movement of the end frames which also move together. As the vanes 39 are located upon the underside of the horizontal frames, when the machine is at rest they will drop by their gravity to the position shown in Fig. 2 and while thus inclined will offer an appreciable resistance to the air and this will tend to move the plane in a forward direction as the frame to which they are attached is moved upward. Upon the reverse or downward movement of said frame, the action of the air will instantly force the vanes to their horizontal position with their margins overlapping, so as to present a continuous surface, which will be at all times vertical to the direction in which the power is applied, thus rendering available the maximum lifting power of the plane. The vanes being quite narrow in comparison with the total area of the plane there will be very little time lost in their opening and closing. In practice I have found that by placing the damping cords 43 in proximity to the hinges, the valves may be easily retained at approximately an angle of 30 to 45 degrees from the horizontal when at their maximum opening, thus limiting their swing on the hinges. I have also found by experiment that the manner of gluing the margin of the vane to parallel cords is of especial advantage, affording a strong attachment. The cords are secured to the frame only at their extremities, and the ends of the sheets or strips forming the vanes are left free from the hinge cords for a short distance at their ends, thus permitting the cords to twist near their attachments and allow the flaps to assume the inclined position without bending or breaking, and preventing any appreciable injury by wear or tear to the hinge construction. The movement of the reciprocating planes in the manner stated

will cause the entire apparatus to rise in an inclined direction, even though the standards are in a vertical position, the deviation from a direct ascent being due to the 5 action of the inclined vanes while the planes are moving upward, as previously mentioned. In order to increase the forward movement all of the guides 26 are inclined forward simultaneously by turning the 10 worm 48, and as the downward action of the reciprocating planes is always parallel with the said guides the planes will exert a pull at such an angle as to carry the entire apparatus on a forward course. If it is required to turn to the right hand or the left, 15 the operator will seize the lever 55 and carry it forward, if he wishes to guide to the right, or backward for a turn in the opposite direction, and this movement will take place 20 whether the middle pairs of guides or standards 26 are vertical or inclined, and if the said lever is moved to a sufficient extent to tilt the outer planes to their maximum degree of inclination the tendency will be 25 to rotate the entire apparatus upon its vertical axis.

It will be noticed by inspection of the drawings that the platform and machinery carried thereon are suspended at a considerable 30 distance below the reciprocating vanes, thus bringing the center of gravity of the apparatus very low so as to give a proper equilibrium, that will sustain the apparatus in an approximately upright and 35 therefore safe position.

In case the motor should be stopped from any cause the apparatus will begin to descend and the vanes of all the frames being 40 instantly forced to their horizontal position, the planes thus formed will resist the action of gravity to a sufficient extent to permit the machine to settle toward the earth at a moderate speed and the shock or jar of contact with the ground will be partially 45 absorbed by the buffer springs 14, so as to prevent breakage of the machinery, or injury to the operator.

Having thus described my invention, what I claim is:—

50 1. In an aerial machine, including a motor, the combination with a supporting frame, of a crank shaft on said frame, vertical guides pivoted on said shaft, a reciprocating frame mounted on guides, movable vanes 55 carried by said reciprocating frame, operative connection between the reciprocating frame and said shaft, and means for inclining said guides relatively to the supporting frame, said means comprising a 60 rock shaft, arms on said shaft, and a flexible connection between the shaft and said guides.

65 2. In an aerial machine, including a motor, the combination with a supporting frame, of a main shaft, a plurality of

cranks on said shaft, vertical guides pivoted on said shaft, and arranged in pairs, a frame adapted to reciprocate on each pair of guides, movable vanes carried by each of said frames, operative connection between each frame and one of said cranks, and means for inclining the said guides relative to the supporting frame, said means including a sectional rock-shaft, gearing connecting the sections of the shaft, said 70 gearing adapted to rotate the shaft sections in opposite directions.

3. In an aerial machine, including a motor, the combination with a supporting frame, a main shaft, guides pivoted on said shaft and a frame adapted to reciprocate on said guides and having vanes mounted thereon, of a rock-shaft arranged parallel with the main shaft and comprising a hollow shaft formed in sections rigidly connected by an offset, and an inner sectional shaft, each section extending entirely through the corresponding outer section and operative connection between said rock shaft and said guides.

4. In an aerial machine, including a motor, the combination with a supporting frame, a main shaft, guides pivoted on said shaft, and frames adapted to reciprocate on said guides and vanes mounted on said frames, of a rock-shaft arranged parallel with the main shaft and comprising a hollow shaft formed in sections rigidly connected by an offset, and an inner sectional shaft, each inner section extending entirely through the corresponding outer section, operative connection between some of said guides and the outer shaft, and operative connection between the remaining guides and the inner shaft.

5. In an aerial machine, including a motor, the combination with a supporting frame, a main shaft, upwardly extending guides pivoted on said shaft, frames adapted to reciprocate on said guides, vanes supported on said frames, and operative connection between the frames and said main shaft, of a rock-shaft arranged parallel with the main shaft, said rock-shaft comprising a hollow shaft having an offset intermediate the ends, an inner shaft comprising sections extending through the portions of the hollow shaft upon each side of the offset, means for independently operating the outer and inner shafts, and operative connection between the said outer and inner shafts and the said guides.

6. In an aerial machine, the combination with a supporting frame, and a motor, of a main shaft mounted on said frame and provided with a plurality of cranks, a pair of upwardly extending guide-rods pivoted on said shaft adjacent each crank, a frame arranged to slide upon each pair of said rods, series of hinged vanes carried by said 125 rods,

frames, a rock-shaft mounted parallel with said main shaft, said rock-shaft comprising an outer and an inner portion telescopically arranged, said inner portion composed of 5 two sections adapted to rock in opposite directions, operative connection between said rock-shaft and said guide rods and means for reciprocating said slidable frames.

7. In an apparatus of the character described, the combination with a supporting frame, and a motor, of a crank shaft provided with a plurality of cranks, a pair of upwardly extending guide rods arranged adjacent each crank and mounted to rock 10 upon said shaft, a frame arranged to slide upon each pair of guide rods, series of hinged vanes carried by said frames, the vanes upon each frame arranged to form a continuous plane when closed upon their 15 hinges, means for rocking some pairs of said guide rods independently of the other pairs, said rocking means comprising a rock shaft, and arms on said rock-shaft connected with said guide rods, and means for 20 reciprocating said frames.

8. In an apparatus for the purpose described, including a supporting frame, and a motor, of a main shaft, a plurality of cranks on said shaft, a pair of upwardly 25 extending guide rods corresponding with each crank, and mounted to rock upon said shaft, reciprocating frames engaging said guide rods, vanes carried by said frames, a rock shaft arranged parallel with said main 30 shaft, said rock shaft comprising two hollow shafts telescopically mounted, rock arms on said hollow shafts, connections between said arms and the guide rods, and means for rocking said shafts independently.

40 9. In an apparatus for the purpose specified, including a supporting frame and a motor, of a main shaft, a plurality of cranks on said shaft, a plurality of pairs of guide rods extending upwardly from said shaft 45 and mounted to rock thereon, reciprocating frames slidable on said rods, planes carried by said frames, each plane comprising hinged vanes adapted to form a continuous surface when closed upon their hinges, a 50 rock shaft comprising a hollow shaft formed in sections rigidly connected, and an inner sectional shaft, means for independently rocking said inner and outer shafts, rock arms on said shafts, operative connection between said arms and the guide rods and means for operating said reciprocating frames.

10. In an apparatus for the purpose specified, including a motor the combination with 60 a supporting frame, a crank shaft provided with a plurality of cranks, guide rods mounted to rock on said shaft, reciprocating

frames slidable on said rods, planes carried by said frames, said planes composed of hinged vanes adapted to be opened and 65 closed by the impact of the air when said frames are operated, a rock shaft comprising an outer hollow shaft formed in sections rigidly connected, an inner shaft also formed in sections, means for rocking the said shafts 70 independently or in unison, and means for rocking the sections of the inner shaft simultaneously in opposite directions, and means for operating said reciprocating frames. 75

11. In an apparatus for the purpose specified, a reciprocating plane composed of a series of flaps formed of rectangular sheets arranged with overlapping margins, hinges for said sheets formed by a plurality of parallel stretched cords to which said sheets are attached by means of a suitable adhesive applied intermediate the ends of the sheets leaving said ends free, and stop cords arranged above and below the flaps to limit 80 their movement.

12. In an apparatus for the purpose specified the combination with a supporting frame, and a motor, of a crank shaft journaled on the frame, a plurality of cranks on 90 said shaft, a pair of upwardly projecting guides mounted to rock on said shaft adjacent each crank, a reciprocating frame carried by each pair of guides, said frame comprising sleeves slidable on said guides, and 95 tubular members attached to said sleeves, a pitman rod connecting each frame with its corresponding crank, planes attached to said frames, said planes comprising hinged valves adapted to be operated by the frame movement, and means for independently rocking the outer and inner pairs of guides. 100

13. In an apparatus for the purpose specified, including a motor, of a supporting platform, a crank shaft supplied with a plurality of cranks, a plurality of reciprocating frames corresponding to said cranks arranged above said platform, operative means connecting each crank with its respective frame, planes carried by 110 said frames, said planes composed of valves adapted to be opened and closed by alternate reciprocal movements of said frames, means for inclining the middle planes and the outer planes independently of each other, and 115 means for simultaneously inclining the said outer planes in opposite directions.

In testimony whereof I affix my signature in the presence of two witnesses.
